CONTROL SYSTEM

Kendall Clark, South Bend, Ind., assignor to
 International Engineering Corporation, a corporation of Illinois

Application November 15, 1937, Serial No. 174,565

8 Claims. (Cl. 158—28)

This invention relates to control systems for oil burners and the like and particularly to a safety means for holding the circuit open when something goes wrong with the burner, and to a control circuit including such means.

An object of the invention is to provide improved automatic means for opening the main circuit of an oil burner or the like in the event that the burner fails to ignite upon starting.

Another object is to provide an effective and simple time delay switch for use in such means. Preferably this is in the form of a thermally actuated time delay switch. I prefer that the time-delay switch used in the described control circuit should be provided with simple manually-operated resetting means. A still further object is to provide a switch such as above described with such manual resetting means combined with additional switch means operable to again start the burner even if it has been automatically rendered inoperative by a stack element such as is normally employed with oil burners, and which functions when the burner fails to operate properly.

In the arrangements herein described these objects are attained by employing a bimetal thermo-static element carrying a contact normally disengaged from a second contact, the two contacts comprising a switch in one of the lines of the main burner circuit, latch means holding the contacts closed and being adapted to release on the heating and flexing of the bimetal element, together with a heater coil for heating the bimetallic element as long as the igniter continues to operate. Since the igniter is turned off automatically when the burner becomes effective, the contacts only separate to break the circuit when something goes wrong and the burner fails to ignite properly.

The above and other objects and features of the invention, including various novel combinations and desirable particular constructions, will be apparent from the following description of the illustrative embodiments shown in the accompanying drawing in which:

Figure 1 is a wiring diagram of one form of control circuit;

Figure 2 is a section through the novel safety device incorporated therein;

Figure 3 is an end elevation of the safety device;

Figure 4 is a wiring diagram of a second embodiment;

Figure 5 is a section through the safety device of said second embodiment; and

Figure 6 is another section through the second safety device, on the line 6—6 of Figure 5.

In the arrangement of Figures 1-3 the system includes a burner having electrically-controlled operating means such as a motor 10 of a type 5 having a starting winding 12 and a running winding 14. An electric igniter, shown as a resistance 16 adapted to become hot enough to ignite the fuel-air mixture issuing from the burner, is connected in series with the starting winding 12 so 10 that they are always on at the same time and off at the same time.

Such burners are usually provided with stack switches such as the one indicated diagrammatically at 18. This switch is arranged on the stack 15 or chimney or chimney connection through which pass the hot burner gases from the furnace with which the burner is associated.

The particular stack switch illustrated has a bimetallic blade 20 in the path of the flue gases, 20 and carrying contacts either engaging (when the burner is not operating and the stack is cold) a contact 22 or (when the blade is acted on by hot flue gases) a contact 24. The blade 20 is arranged to move rapidly from contacts 22 and 25 to contact 24 as the hot combustion products actuate it, and to return slowly from contact 24 to contacts 22 and 26 as blade 20 cools after the combustion ceases. The contact 22 is yieldingly mounted, and when the blade 20 is cold 30 it forces the contact 22 against a fourth contact 26. When the burner is operating, contacts 22 and 26 spring apart.

The system includes operating circuit lines 30 and 32, connected to a source of alternating current electrically under the control of the usual room-thermostat switch 33. Disregarding the safety device described below, when the burner is not operating the circuit is from line wire 30 to the contacts on blade 20 and thence, in two parallel paths (1) contact 22—starting winding 12—igniter 16 and (2) contact 22—contact 26—running winding 14, to the other line wire 32. When the burner starts and blade 20 actuated by the heat of combustion, shifts to close the contact 45 24 and open contacts 22—26, the circuit is from wire 30—blade 20—contact 24—running winding 14—line wire 32.

The novel safety device in one structural form is shown in Figures 2 and 3. It includes a base 40 50 on which is mounted a fixed contact 42 having a binding post 44, a yielding contact 46 normally sprung away from contact 42 and having a binding post 48, and a bimetallic blade 50 secured to the base 40 at one end and tensioned to spring 55

away from contact 46 but movable against its own yielding resistance to engage the contact 46.

The free end of the blade 50 is formed as a latch 52 extending through an opening in the base 40 and yieldingly interlocking therewith to hold the blade 50 against the contact 46. The base 40 also supports a heating resistance 54 having at one end a binding post 56 and having its other end secured electrically to the blade 50 by a handle 58 which serves as manually-operable means for engaging the latch 52 with the base. The handle 58 also serves as means by the manual operation of which the contact 46 can be forced against the contact 42. A cover 60, having an opening 62 for the handle 58, may also be provided.

The line wire 30 is connected through binding post 56 to the resistance 54; the contact 46 is connected through binding post 48 and a wire 64 to the bimetallic blade 20 of the stack switch; and the contact 42 is connected through binding post 44 and a wire 66 direct to the starting winding 12 independently of the stack switch.

In operation, when the room thermostat closes the circuit to turn on the burner, the circuit is from wire 30 through resistance 54, to blade 50, contact 46, wire 64, blade 20, and thence to line wire 32 through the parallel circuits (1) contact 22—starting winding 12—igniter 16, and (2) contact 22—contact 26—running winding 14.

The electrical resistance of the above-mentioned circuit (1) is of a much lower value than circuit 2, and the combined parallel circuits cut down the total resistance so that a fairly heavy current flows through the resistance 54. Normally the burner starts promptly, causing the stack switch 18 to operate, and the circuit is then: line wire 30—resistance 54—blade 50—contact 46—wire 64—blade 20—contact 24—running winding 14—line wire 32. This circuit has a fairly high overall resistance, and not enough current flows through it to heat the resistance 54 enough to affect the bimetallic blade 50.

If, however, the burner for any reason fails to ignite, after a short predetermined interval the heavy current flowing through the parallel circuits 1 and 2 heats resistance 54 and deforms the blade 50 enough to release the latch 52, whereupon the circuit is automatically suddenly broken, and will remain open until closed again manually. After making any necessary repairs, the operator lifts the handle 58 to cause the latch 52 to re-engage.

The stack switch blade 20 sometimes sticks in the hot position or reaches some intermediate position after the room thermostat opens and consequently, when the space being heated has cooled off and the thermostat again closes, the burner will not start. The stack switch is often in an inaccessible position and generally it would be beyond the ability of the average user to repair it, so I have provided an auxiliary circuit which can be closed by raising the handle 58 high enough to close the contacts 46—42. This circuit goes directly through the starting winding 12 and the igniter 16 independently of the stack switch.

The handle must be held up until ignition actually takes place, since, if it were released, the igniter would be de-energized while the motor 10 would continue to run and discharge oil into the furnace. If ignition takes place, the burner will operate all right until the room thermostat opens. If it does not take place, the oper-

ator need only push down on the handle 58 to release the latch 52 to stop the motor.

I have observed that if a burner in which the stack switch has stuck is caused to operate, the reheating often releases the mechanism of the switch and it will operate thereafter for a long time without further trouble or need of repair. Consequently, my novel auxiliary circuit may result in saving of repair bills, but even if this does not occur it affords means of obtaining heat in the interval between the discovery of the trouble and the arrival of a service man. Another advantage of my novel circuit arises in placing this auxiliary circuit and switch in conjunction with the lockout switch reset so that no confusion arises as to the means of restarting the burner when it fails to operate.

The control system also functions as a safety device against a failure of the source of electric power. A safety device is very essential for oil burning systems of the type described above having intermittent ignition. It is essential to insure that the ignition device be in operation when the burner starts after a short current interruption; otherwise oil and air in an explosive mixture ratio are introduced into the combustion chamber, and subsequent ignition might cause a disastrous explosion. In the event of power failure, the motor 10 stops and the oil burner no longer operates. When the power is turned on again, the motor 10 has its running winding 14 connected to lines 30 and 32, but it cannot start as its starting winding 12 has been disconnected.

The arrangement of Figures 4-6 differs from that described above only in that the heating resistance 154 is connected at its ends to binding post 56 and, through a conducting bracket 155, to binding post 44. The blade 50 has its own binding post 150, to which line wire 30 is connected. This connects the resistance 154 between the starting wind 12 and the contact 22, so that it is not in the running winding circuit and no current passes through it when the burner is running.

While two illustrative embodiments have been described in detail, it is not my intention to limit the scope of the invention to those particular embodiments, or otherwise than by the terms of the appended claims.

I claim:

1. A control system for an oil burning furnace or the like comprising, in combination with a burner mechanism including a motor with a starting winding and a running winding and an igniter device, and with operating circuit lines, a stack switch normally connecting said lines through both windings and through the igniter device when the burner is not operating and the furnace is cooled and normally connecting said lines through the running winding only when the burner is operating and the furnace is hot, and a safety switch connected in one of said lines and which is not affected by the current passing when the circuit is closed through the running winding only and which is provided with means for automatically opening the circuit and locking it open when the current passes for a pre-determined time through the igniter and through both windings without starting the burner, said safety switch having manually operable means for closing an auxiliary circuit between said lines around the stack switch and directly through the igniter device and through the starting winding, whereby the burner can

be started in the event the stack switch fails to return to the cold position.

2. A control system for an oil burning furnace or the like comprising, in combination with a burner mechanism including a motor and an igniter device, and with operating circuit lines, a stack switch normally connecting said lines through said motor and through the igniter device when the burner is not operating and the furnace is cooled and normally connecting said lines through the motor only when the burner is operating and the furnace is hot, and a safety switch connected in one of said lines and which is not affected by the current passing when the circuit is closed through the motor only and which is provided with means for automatically opening the circuit and locking it open when the current passes for a pre-determined time through the igniter and through the motor without starting the burner, said safety switch having manually operable means for closing an auxiliary circuit between said lines around the stack switch and directly through the igniter device and through the motor, whereby the burner can be started in the event the stack switch fails to return to the cold position.

3. A control system for an oil burner or the like comprising, in combination with operating circuit lines and a burner having electrically-controlled operating means and with an igniter, means for connecting said lines through both said first means and the igniter when the burner is first turned on and for connecting said lines through said first means only after the burner starts, and a safety device connected to open the circuit automatically after a predetermined time during which the current passes through both said first means and the igniter, if the burner does not start, said safety device including means manually operable when the circuit is open for closing the circuit from said lines around the second means directly through the igniter device and said first means.

4. A control system for an oil burner or the like comprising, in combination with operating circuit lines and a burner having electrically-controlled operating means and with an igniter, means for connecting said lines through both said first means and the igniter when the burner is first turned on and for connecting said lines through said first means only after the burner starts, and a safety device connected to open the circuit automatically after a predetermined time during which the current passes through both said first means and the igniter, if the burner does not start, said safety device including means manually operable when the circuit is open for closing the circuit from said lines around the second means directly through the igniter device and said first means, said safety device being provided with latch means operating automatically when the circuit is opened to hold the circuit open until closed manually.

5. A control system for an oil burner or the like comprising, in combination with operating circuit lines and a burner having electrically-controlled operating means and with an igniter, means for connecting said lines through both said first means and the igniter when the burner is first turned on and for connecting said lines through said first means only after the burner starts, a normally-stationary member having a contact and a bimetallic blade having a contact engaging the first contact and which contacts are connected in one of said lines in series with

a heating resistance adjacent said blade to open the two contacts after a predetermined interval during which current passes through both the igniter device and said first means, said blade having a latch normally holding the contacts closed against the yielding resistance of said blade and which is released by the deformation of the blade caused by heating it during said predetermined interval, manually operable means for re-latching said blade with the contacts closed, said stationary member being yieldable with the bimetallic blade when said contacts are engaged and the manually operable means is operated, and a third contact engaged by the first contact when said member so yields and which closes an auxiliary circuit directly through the igniter and through said operating means around said second means.

6. A control system for an oil burner or the like comprising, in combination with operating circuit lines and a burner having electrically-controlled operating means and with an igniter, means for connecting said lines through both said first means and the igniter when the burner is first turned on and for connecting said lines through said first means only after the burner starts, a normally-stationary member having a contact and a bimetallic blade having a contact engaging the first contact and which contacts are connected in one of said lines in series with a heating resistance adjacent said blade to open the two contacts after a predetermined interval during which current passes through both the igniter device and said first means, manually operable means for moving said blade against its own yielding resistance to re-engage said contacts, said stationary member being yieldable with the bimetallic blade when said contacts are engaged and the manually-operable means is operated, and a third contact engaged by the first contact when said member so yields and which closes an auxiliary circuit directly through the igniter and through said operating means around said second means.

7. A control system for an oil burner of the like comprising, in combination with operating circuit lines and a burner having electrically-controlled operating means and with an igniter, means for connecting said lines through both said first means and the igniter when the burner is first turned on and for connecting said lines through said first means only after the burner starts, a normally stationary member having a contact and a bimetallic blade having a contact engaging the first contact, said contacts being arranged in one of said lines, a heating resistance connected in the part of the circuit including the igniter and arranged adjacent said blade to heat the blade as long as the igniter is on to open the circuit automatically after a predetermined interval if the igniter is not turned off, said blade having a latch normally holding the contacts closed against the yielding resistance of said blade and which is released by the deformation of said blade caused by being heated by said resistance, manually-operable means for re-latching said blade with the contacts closed, said stationary member being yieldable with the bimetallic blade when said contacts are engaged and the manually-operable means is operated, and a third contact engaged by the first contact when said member so yields and which closes an auxiliary circuit directly through the igniter and through said operating means around said second means.

8. A control system for an oil burner or the like comprising, in combination with operating circuit lines and a burner having electrically-controlled operating means and with an igniter,
5 means for connecting said lines through both said first means and the igniter when the burner is first turned on and for connecting said lines through said first means only after the burner starts, a normally stationary member having a contact and a bimetallic blade having a contact engaging the first contact, said contacts being arranged in one of said lines, a heating resistance connected in the part of the circuit including the igniter and arranged adjacent said blade to
10

heat the blade as long as the igniter is on to open the circuit automatically after a predetermined interval if the igniter is not turned off, manually-operable means for moving said blade against its own yielding resistance to re-engage said contacts, said stationary member being yieldable with the bimetallic blade when said contacts are engaged and the manually-operable means is operated, and a third contact engaged by the first contact when said member so yields and which closes an auxiliary circuit directly through the igniter and through said operating means around said second means. 5
10

KENDALL CLARK.
